[57] CLAIM

The ornamental design for a wine rack, substantially as shown and described.

DESCRIPTION

FIG. 1 is a top perspective view of the wine rack showing my new design;

FIG. 2 is a top plan view thereof;

FIG. 3 is a front elevational view, the rear being identical thereto;

FIG. 4 is a right side elevational view, the left side being identical thereto;

FIG. 5 is a bottom plan view thereof;

FIG. 6 is a sectional view taken along line 6—6 of FIG. 2;

FIG. 7 is a sectional view taken along line 7—7 of FIG. 3; and

FIG. 8 is a front elevational view of a modified form of the wine rack shown in FIG. 1, the rear view being identical thereto; the sides not shown are identical to those of FIGS. 2, 4, and 5 with the addition of a third stackable element.

FIG. 1

FIG. 5

FIG. 6

FIG. 7

FIG. 8
